UNITED STATES PATENT OFFICE.

WILLIAM E. GEORGE, OF HARLAN, IOWA, ASSIGNOR OF ONE-HALF TO
JOHN COENEN, OF SAME PLACE.

CONVERTIBLE STOCK-WAGON.

SPECIFICATION forming part of Letters Patent No. 374,591, dated December 13, 1887.

Application filed August 17, 1887. Serial No. 217,185. (No model.)

To all whom it may concern:

Be it known that I, WILLIAM E. GEORGE, a citizen of the United States, residing at Harlan, in the county of Shelby and State of Iowa, have invented certain new and useful Improvements in Convertible Stock-Wagons; and I do hereby declare the following to be a full, clear, and exact description of the invention, such as will enable others skilled in the art to which it appertains to make and use the same.

This invention relates to improvements in wagons; and it consists in the novel construction and arrangement of the same, whereby the body of the wagon may be used for hauling stock and converted into a hay-wagon, as well as using it as any common wagon is used, all as will be hereinafter fully explained, and particularly pointed out in the appended claims.

20 The annexed drawings, to which reference is made, fully illustrate this invention, in which—

Figure 1 represents a perspective view showing the wagon as used for hauling stock. Fig. 2 represents the same converted into a hay-wagon. Fig. 3 is a perspective view of one of the braces. Fig. 4 is a detail sectional view of the hook-and-eye portion of the chute and wagon. Fig. 5 is a detail view.

30 Referring by letter to the accompanying drawings, A is the wagon-body, consisting of the lower fixed portion, a, movable upper side portions, b, and detachable end gate c, which serves also as an inclined chute or platform for permitting the stock to enter the wagon. The fixed body portion is braced in the usual manner, as at d, having the side or short standards, e, to which are secured the side rails, f, above the side-boards g. The vertically-expanded sides b of the body are hinged to the fixed portion a, as at i, and are connected by the front rod, j, and rods k k, which hook in eyes or staples l l, as shown. The end-gate or chute is constructed with sides m, and the floor thereof has cross-cleats, whereby the stock can have a sure footing in ascending the incline, and on the under side of the wagon-body are arranged hooks n n, which engage eyes or staples o o on said chute, thus forming a detachable hinged connection for the latter. The sides of said chute are provided with hooks p p, which engage eyes q q on the side of the upper portion on the wagon-body.

In combination with the hinged sides of the

wagon are used detachable supporting-brackets B, which are used to support the sides when down to form a hay-wagon, as shown in Fig. 2 of the drawings. These brackets are constructed with a vertical portion, r, an oblique strip, s, and a horizontal piece, t, which latter projects both front and rear, as shown at u and v, while the upper end of the oblique strip projects above the horizontal bar, as at w. It will be seen that when the sides are let down for converting the body into a hay-wagon the bracket is attached to the body by resting the projecting end v of the horizontal bar on the side rail, f. At the same time the extended end w of the oblique strip s is inserted between the side rails of the movable upper portion, thus bringing the weight upon said bracket, which in turn is braced by the fixed sides of the wagon-body. It will thus be further observed that the chute serves to close the rear end of the wagon and can be detached therefrom when desired, and the same can be attached to any common wagon, and the brackets are constructed in such a manner that they require no additional fastening devices to keep them in place for supporting the sides or racks, and by removing the racks from the fixed body the latter can be used for general purposes—such as hauling corn, manure, &c.—and the parts are simple of operation, durable, and cheap to manufacture.

What is claimed is—

1. In a stock-wagon, the combination, with the fixed body portion and hinged side racks, of the brackets having the projecting ends, as described, for attachment to the body and rack and for supporting the latter, as described, and for the purpose set forth.

2. In combination with the hinged side racks and wagon-body, the detachable bracket comprising the vertical strip r, horizontal strip t, and oblique strip s, secured to one another, said horizontal strip having the front projecting end, u, and projecting rear end, v, and the oblique strip having the projecting end w, for the purpose set forth.

In testimony whereof I affix my signature in presence of two witnesses.

WILLIAM E. GEORGE.

Witnesses:

PATRICK H. HUNT,
JOSEPH STILES.
